UNITED STATES PATENT OFFICE.

MARGARITO CABRERA, OF SAN ANTONIO, TEXAS.

COTTON-CLEANER.

1,303,026.

Specification of Letters Patent.

Patented May 6, 1919.

Application filed July 7, 1916. Serial No. 108,011.

To all whom it may concern:

Be it known that I, MARGARITO CABRERA, a citizen of the Republic of Mexico, residing at San Antonio, in the county of Bexar and 5 State of Texas, have invented certain new and useful Improvements in Cotton-Cleaners; and I do hereby declare the following to be a full, clear, and exact description of the invention, such as will enable others skilled 10 in the art to which it appertains to make and use the same.

This invention relates to cotton cleaners, and the primary object of the invention is to provide a cotton cleaner wherein the cotton 15 ton is drawn into and through the cleaner by air suction, which cleaner casing is provided with a pair of hinged sections, so that the interior of the cleaner may be easily and quickly released, and also so that in case the 20 cotton within the cleaner catches fire, the sides may be opened, allowing the rotor of the cleaner to throw the dirty cotton out of the cleaner, and owing to the fact that cotton is drawn into and through the cleaner by air 25 suction, the feeding of the cotton into the cleaner will be arrested because the opening of the sides of the casing will break the direct line of air suction.

Another object of this invention is to provide 30 a cotton cleaner as specified which includes a plurality of rotary members having radially extending webs carried thereby which carry the cotton over foraminous screens through which the foreign matter is 35 forced, which structure is arranged for thoroughly cleaning the cotton fiber without twisting the same and further to provide agitators at the end of the cleaner which will fluff or loosen the cotton prior to and after 40 passage through the cleaner.

With the foregoing and other objects in view this invention consists in such novel features of construction, combination and arrangement of parts as will be hereinafter 45 more fully described, illustrated in the accompanying drawings and claimed.

In describing the invention in detail reference will be had to the accompanying drawings wherein like characters designate 50 like and corresponding parts throughout the several views, and in which:—

Figure 1 is a side elevation of the improved cleaner having the parts thereof broken away,

55 Fig. 2 is a horizontal section through the improved cleaner,

Fig. 3 is an end view of the cleaner,

Fig. 4 is a vertical section through the cleaner,

Fig. 5 is a detail perspective view of one 60 of the rotary members of the cleaner, and

Fig. 6 is a fragmentary section through the cleaner illustrating one of the agitating or fluffing members.

Referring more particularly to the drawings, 1 designates the casing of the cotton cleaner, which is substantially heart shaped. A flue 2 is carried by the top of the casing 1 and it has valves 3 and 4 positioned therein as clearly shown in Fig. 1 of the drawings. 70 Any suitable type of air suction device may be connected to one end of the flue 2 for drawing cotton inwardly into the cleaner through the end 5 and outwardly out of the cleaner through the end 6. The valves 3 75 and 4 are provided for regulating or cutting off the air suction.

The sections 7 and 8 of the casing 1 are hingedly connected as shown at 9 to the flue 2, so that they may be moved outwardly for 80 permitting access to the interior of the cleaner if it is so desired.

A plurality of supporting braces 10 are positioned at spaced distances interiorly of the casing 1 and they support the lower sections of the foraminous screens 11. The sections 7 and 8 have portions 12 of screen attached thereto the lower edges of which meet with the edges of the portion 11 as clearly shown in Fig. 4 of the drawings for 90 forming a continuous foraminous lining within the cleaner over which the cotton is passed through the rotary action of the rotors 14 and 15. The rotors 14 and 15 are mounted upon shafts 16 and 17 respectively, 95 which shafts are rectangular intermediate their ends, upon which rectangular portions the rotors are mounted. The shafts 16 and 17 project outwardly out of the ends of the casing and they are supported by suitable 100 bearings or pillow blocks 18. The shaft 16 has a driving pulley 19 mounted upon one end of the same and a gear 20 mounted upon the other end. The gear 20 meshes with a gear 21 which is mounted upon the shaft 105 17 whereby the shaft 17 will be rotated by the shaft 16 in an opposite direction to the rotation of the shaft 16 and the rotor carried thereby. The rotors 14 and 15 comprise cores or cylindrical hubs 23 which have 110 a plurality of ribs or radiating blades 24 attached thereto. The blades 24 are straight

and extend longitudinally of the cylindrical cores 23, so as to carry the cotton over the screen structures 12 and 11 without twisting the fiber or strands of the cotton.

- 5 The shafts 16 and 17 have agitators or fluffers 25 mounted thereon at each end of the casing 1. The fluffers 25 include hub sections 26 which have a plurality of radiating blades 27. The blades 27 during the 10 rotation of the fluffers 25 engage the cotton fiber as it enters the casing 1 and loosen or fluff it so that the cleaning action of the rotors 14 and 15 may be facilitated while the agitators or fluffers 25 which are positioned at the delivery end of the cleaners 15 loosen or fluff the cotton prior to its passage from the cleaner to a gin.

An auger conveyer 30 is positioned in the bottom of the casing 1 and it is provided for 20 carrying off the foreign matter which is rubbed from the cotton fiber.

The cotton is drawn into the cleaner through the end 5 of the flue 2 by air suction and upon its entrance into the casing 25 1 it is engaged by the fluffers 25 positioned at the receiving end of the cleaner which loosen or fluff the cotton. The cotton is then drawn through the casing by the air suction, and it is carried over the screen 30 linings 12 and 11 by the action of the rotors 14 and 15 which will rub dirt, small particles of stems, pods or leaves from the fiber and through the screens 12 and 11 into the lower portion of the casing 1, from 35 which it is conveyed by the auger conveyer 30. The cleaned cotton will be drawn outwardly through the end 6 of the flue 2 for passage through a gin or storage house as desired.

40 In case the cotton within the cleaner catches fire, the hinged sections 7 and 8 of the casing 1 may be moved outwardly, which will permit the rotation of the rotors 14 and 15 to throw the cotton out of the cleaner

upon the floor. When the sides 7 and 8 are 45 open, the air suction through the cleaner will be broken, and consequently the feeding of cotton into the cleaner will be arrested. Immediately after the sides are again closed, the air suction will be complete and the feeding of the cotton will be resumed. 50

From the foregoing description taken in connection with the accompanying drawings, the advantages of construction and of 55 the method of operation of the improved cotton cleaner will be readily apparent to those skilled in the art to which this invention appertains, and while in the foregoing description, the principle of the operation 60 of this invention has been described together with various features of construction, it is to be understood that certain minor features of construction, combination and arrangement of parts may be altered to suit 65 practical conditions provided such alterations are comprehended within the scope of what is claimed.

What is claimed is:—

In a cotton cleaner structure, a rotor comprising a core, a plurality of radiating blades carried by said core constructed of sheet metal bent to form curved core engaging portions and having one longitudinal edge thereof bent outwardly at right angles 70 to form straight radiating blade portions, the opposite longitudinal edge of each curved portion engaging the facing surface of the blades next thereto to prevent relative movement between the blades and to 75 inclose said core.

In testimony whereof I affix my signature in presence of two witnesses.

MARGARITO CABRERA.
